UNITED STATES PATENT OFFICE.

PRESTON UPHAM, OF BOSTON, MASSACHUSETTS, ASSIGNOR TO SULLIVAN MACHINERY COMPANY, OF BOSTON, MASSACHUSETTS, A CORPORATION OF MASSACHUSETTS.

MINING MACHINE.

Application filed July 26, 1916. Serial No. 111,523.

This invention pertains to mining machines and more particularly, though not exclusively, to coal mining machines employing movable cutting devices adapted to be presented to the coal to cut a kerf or channel therein.

The invention will be best understood by reference to the following description, in connection with the accompanying drawings, 10 which description and drawings relate to a preferred construction of one specific embodiment of my invention, while the scope of my invention is more particularly pointed out in the appended claims.

15 Referring to the drawings:

Fig. 1 is a plan of a machine constituting one embodiment of my invention;

Fig. 2 is a side elevation thereof;

20 Fig. 3 is a vertical, longitudinal, sectional elevation thereof, on the line 3—3 of Fig. 1;

Figs. 4 and 5 are vertical, transverse, sectional elevations thereof on the lines 4—4 and 5—5, respectively, of Fig. 1;

25 Fig. 6 is a vertical section, showing a detail of the tilting or elevating mechanism; and,

Figs. 7, 8 and 9 are diagrammatic views illustrating the various operations of the machine when engaged in entry cutting.

While my invention is by no means 30 restricted to feeding, guiding and positioning mechanism, it pertains largely thereto, and for this reason I have shown my feeding and positioning mechanism, system and connections as used with a preferred type of chain 35 cutter machine heretofore largely used for cutting coal while sliding on the mine bottom and while being fed, guided, and positioned by flexible tension members in a manner which may resemble somewhat the 40 mechanism of the patent to Mitchell, No. 656,414, and the mechanism shown in the patent of Jacob M. London, No. 1,635,488, granted July 12, 1927.

45 Among the purposes of the present invention is to promote the more rapid driving of entries in coal mines. The most efficient method of driving such entries heretofore used has been to undercut the entry as shown in the London application, and then to blast 50 down the coal. The safety laws prevent the use of explosives while miners other than "shot firers" are in the mine. The blasting operations usually take place but once a day,

thus limiting the advance in any one entry to one undercut per day. By the use of the 55 preferred embodiment of my invention herein described, several intersecting kerfs can be cut in the heading of the entry, thereby so weakening the structure of the coal that it can be removed without blasting or with a 60 minimum of blasting. This system is to be differentiated from the various machines which are intended to disintegrate all the coal in the heading, for such systems necessarily involve much unnecessary breaking up 65 of the coal, with consequent loss of value of the product and with resultant slowness of operation. The present disclosure should also be differentiated from those machines 70 wherein the cutter bar is mounted for universal movement relative to the actuator of the machine.

In the specific embodiment of my invention illustrated in the drawings, I have shown a chain coal cutting machine of the Mitchell 75 type, comprising the shoe 1, the cutter bar 2, the orbitally movable cutter chain 3, and the main body 4 of the machine to which the cutter bar 2 is preferably rigidly attached. The main body 4 of the machine preferably 80 contains a motor of any suitable form but preferably pressure fluid or electric, and connections from the motor to drive the cutter chain 2 and the flexible positioning means (not shown) which may, if desired, be substantially identical with that shown in the 85 application of Jacob London before mentioned.

I prefer to mount the machine on a truck, comprising the wheels 5 and the body portion 6, relative to which the machine 4 is preferably longitudinally slidably movable in guides 7 forming part of the frame 6, and contacting with the longitudinally movable guiding element 8.

To provide for swinging cutting movement of the cutter bar 2 I preferably employ a turntable 9, operatively interposed between the main body 4 of the machine and the longitudinally movable guiding element 8. 100 This turntable is preferably adapted to permit swinging movement of the cutter bar 2 only in the plane of said cutter bar.

The machine, in so far as already described, is adapted to perform only those 105 operations which could be performed by the

London machine, viz, to cut kerfs by rectilinear or swinging feeding movement of the cutter bar in a plane parallel with the plane of the trackway 10—10. It is one of the purposes of the present invention to provide a machine capable of cutting a series of intersecting kerfs, each being cut by longitudinal and swinging movement of the cutter bar 2. To this end (Fig. 8) I provide a transverse pivotal support 11 for the turntable 9 and the superimposed mining machine 4, which pivotal support during the operation of the machine should be aligned with the line of longitudinal feeding movement of the machine. It is clear that when the turntable 9 with the superimposed mechanism is tipped about this axis of the transverse pivotal support 11 the machine may be advanced to cut a kerf into the work in any one of a plurality of different angles relative to the horizontal while keeping the cutter bar in a plane during the cutting of any one of such kerfs. To provide for the cutting of kerfs inclined either to the right or to the left, and to avoid the necessity for more than one pivot, I preferably provide a supplementary turntable 12, operatively interposed between the longitudinally movable guiding member 8 and the transverse pivotal support 11, whereby said transverse pivotal support may be located at either side of the apparatus, thus providing for the cutting of kerfs disposed either to the right as 13, 14, 15 (Fig. 9), or to the left as 16, 17, 18 (Fig. 9).
 35 For other purposes, the transverse pivotal support may be located at any desired angle, one of which is shown in Fig. 1. Any suitable locking means, such for example as the pin 12' may be provided to hold the turntable 12 in any desired relation to the longitudinally movable guiding member 8. Any suitable locking means, such for example as the pin 9' may be provided to hold the turntable 9 in the desired relation to the pivoted support 19 during longitudinal feeding movement of the machine. While the angle of the pivoted support 19 may be adjusted in any other suitable manner, I prefer to provide a manually operable train of gears operating with screw mechanism and to this end I have shown a hand wheel 20 on a shaft 21, having keyed thereto a pinion 22 which meshes with a gear 23 co-axial and rotatable with a bevelled pinion 24 which meshes with a bevel gear 25, to which may be attached by a universal joint 26 the female threaded sleeve 27 surrounding the correspondingly threaded screw 28 universally pivoted to a bracket 29 secured to the tilting support 19.
 60 It is thus clear that manual turning of the handwheel 20 will cause the tilting support 19 to be raised or lowered as desired.
 The foregoing apparatus is thus provided with one form of means permitting the positioning of the orbitally movable cutting de-

vices along different elements of the surface of a cone, a cylinder in this connection being regarded as one form of cone, as is common in geometric phraseology.

In operation, the apparatus is preferably located on tracks 10 substantially aligned with the entry to be driven. The initial cut may be horizontal, as the kerf 30 (Fig. 9), which may be and preferably is cut by holding the cutter bar 2 at a fixed angle relative to the axis of the entry and advancing the machine either relative to or with the truck until the cutter bar attains the position shown at 31 in Fig. 7, after which the cutter bar 2 is swung through an arc to the position shown at 32 in Fig. 7, when the machine is again angularly fixed and retracted to complete the kerf 30. Assuming the transverse pivot 11 of the swinging support 19 to be aligned with the line of advance of the machine and at the right thereof as in Fig. 8, the machine may then be adjusted by tilting of the tilting support 19 to repeat the kerf cutting operation in cutting the kerfs 18, 17, 16 or any desired number of similar kerfs, depending on the thickness of the vein, the nature of the coal, and the like. If desired, the turntable 12 may then be swung to align the transverse pivot 11 on the opposite side of the machine, thereby permitting kerfs 13, 14 and 15 (Fig. 9) to be cut. The coal being thus traversed by such a large number of kerfs will either fall down or be easily removable without the use of an explosive agent or with only a minimum amount of shooting.

Where desired, I may dispense with the wheeled truck, thereby enabling the horizontal kerf 30 to be made nearer the floor of the mine.

While for the purposes of illustration I have herein shown and described one specific embodiment of the invention, it is to be understood that the same is not limited to the constructional details and parts or their relative arrangement herein specifically indicated, but that extensive deviations may be made from the described embodiment, without departing from the spirit of the invention, and that many features herein described in combination may be usefully employed independently, or in other connections than in the relations they occupy in the described type of machine.

My invention and what I desire by Letters Patent to secure is best defined in the following claims.

I claim—

1. The combination with a mining machine adapted to slide upon its own bottom upon a mine bottom during cutting, of means for supporting the machine out of contact with the mine bottom and with a different surface nearest to the mine bottom for cutting in a substantially vertical plane, said

machine being movable longitudinally relative to said means during cutting.

2. The combination with a mining machine adapted to slide upon its bottom upon a mine bottom during cutting and provided with a cutter bar, of means for supporting said machine during cutting in positions wherein said bar will be substantially parallel to horizontal or vertical planes.

3. The combination with a mining machine adapted to slide upon its bottom upon a mine bottom during cutting and provided with a cutter bar, of means for supporting said machine during cutting in positions wherein said bar will be parallel to a single inclined plane.

4. The combination with a mining machine adapted to slide upon its bottom upon a mine bottom during cutting and provided with a cutter bar, of means for supporting said machine during cutting in different positions, said bar in each of a plurality of said positions being adapted to be parallel to a single one of a plurality of differently inclined planes.

5. The combination with a mining machine adapted to slide upon its bottom upon a mine bottom during cutting and provided with a cutter bar, of means for supporting said machine during cutting in positions wherein said bar will be parallel to horizontal, vertical or inclined planes.

6. The combination with a mining machine adapted to slide upon its bottom upon a mine bottom during cutting and having a cutter bar fixedly projecting therefrom in alignment with the major dimension thereof, of means for supporting said machine during cutting whereby said bar may cut an opening larger than itself in a substantially vertical plane.

7. The combination with a mining machine adapted to slide upon its bottom upon a mine bottom and having a cutter bar projecting fixedly therefrom in alignment with the major dimension thereof, of means for angularly supporting said machine during cutting whereby the same may cut in a plane inclined to the horizontal.

8. The combination with a mining machine adapted to slide upon its bottom upon a mine bottom during cutting and having a cutter bar projecting therefrom, of supporting means therefor including a horizontal guideway, a carriage slideable longitudinally thereof, and a platform to which said mining machine is secured pivotally mounted with respect to said carriage for angular movement about a horizontal axis.

9. The combination with a mining machine adapted to slide upon its bottom upon a mine bottom during cutting and having a cutter bar projecting therefrom, of supporting means therefor including a horizontal guideway, a carriage slideable longi-

tudinally thereof, and a platform to which said mining machine is secured pivotally mounted with respect to said carriage for angular movement about a horizontal longitudinally extending axis.

10. The combination with a mining machine adapted to slide upon its bottom upon a mine bottom during cutting and having a cutter bar projecting therefrom, of supporting means therefor including a horizontal guideway, a carriage slideable longitudinally thereof, a platform to which said mining machine is secured pivotally mounted with respect to said carriage for angular movement about a horizontal axis, and means between the mining machine and platform permitting swinging movement of the machine upon an axis perpendicular to the plane of the platform.

11. The combination with a mining machine adapted to slide upon its bottom upon a mine bottom during cutting and having a cutter bar projecting therefrom, of supporting means therefor including a horizontal guideway, a carriage slideable longitudinally thereof, a platform to which said mining machine is secured pivotally mounted with respect to said carriage for angular movement about a horizontal longitudinally extending axis, and means between the mining machine and platform permitting swinging movement of the machine upon an axis perpendicular to the plane of the platform.

12. In a mining apparatus, in combination, a machine comprising a base movable longitudinally during cutting, a support mounted on said base and horizontally pivoted thereto by a hinge the axis of which is parallel to the longitudinal movement of said base during cutting, said support being movable about the hinge axis into substantially horizontal and vertical positions, and self-contained cutting mechanism comprising a cutter bar which carries cutting elements orbitally movable relative thereto, said mechanism being pivoted to said support to permit bar swing in substantially the plane thereof and said bar being swingable into extreme cutting positions at opposite sides of said hinge axis.

13. In a mining apparatus, in combination, a machine comprising a base movable longitudinally during cutting, a support mounted on said base and horizontally pivoted thereto by a hinge the axis of which is parallel to the longitudinal movement of said base during cutting, said support being movable about the hinge axis into substantially horizontal and vertical positions, and cutting mechanism comprising a cutter bar carrying cutting elements orbitally movable relative thereto, said mechanism being pivoted to said support to swing in substantially the plane thereof to position the bar in extreme cutting positions at opposite sides

of a line parallel to the hinge line and said support hinge being disposed at one edge of said base.

14. In a mining apparatus, in combination, a machine comprising a base movable longitudinally during cutting, a support mounted on said base and hinged thereto for swinging movement about an axis parallel to the direction of the longitudinal movement of the base during cutting into a substantially vertical position, and cutting mechanism comprising a cutter bar having cutting elements orbitally movable thereon, said mechanism being pivotally mounted on said support to swing in planes closely adjacent and parallel to said pivot, said axis being disposed at one edge of said base and said bar being disposable wholly above said hinge line when said support is in substantially vertical position to cut in such dis-

position.

15. In a mining apparatus, in combination, a machine comprising a base movable longitudinally during cutting, a support mounted on said base and hinged thereto for swinging movement about an axis parallel to the direction of longitudinal movement of said base during cutting to allow a substantially vertical cut to be made, and cutting mechanism comprising a cutter bar carrying cutting elements orbitally movable relative thereto, and pivotally mounted on said support for swinging movement in substantially the plane of the latter and operative to cut kerfs extending above and below the plane of said horizontal axis, said axis being disposed at one edge of said base.

16. In a mining apparatus, in combination, a machine comprising a base movable longitudinally during cutting, a support mounted on said base and horizontally pivoted thereto by a hinge the axis of which is parallel to the longitudinal movement of said base during cutting to allow a substantially vertical cut to be made, and cutting mechanism comprising a cutter bar carrying cutting elements orbitally movable relative thereto, said mechanism being pivoted to said support to swing in substantially the plane thereof, said bar when horizontally disposed lying wholly above said horizontal axis and being operative to cut its way into the coal when advanced bodily in such position, said axis being disposed at one edge of said base.

17. In a mining apparatus, in combination, a machine comprising a sub-base, a base pivoted for rotation about a vertical pivot on said sub-base, said sub-base and base being movable longitudinally during cutting, a support mounted on said base and horizontally pivoted thereto by a hinge the axis of which is parallel to the longitudinal movement of said base during cutting, and cutting mechanism comprising a cutter bar

carrying orbitally moving cutting elements pivoted to said support to swing in substantially the plane thereof, said support hinge being disposed at one edge of said base and said base being pivotable upon its vertical axis to dispose said hinge at either side of said machine.

18. A mining machine comprising cutting mechanism, means whereby the same may be fed forward, means to guide it in its feeding movement, means to adjust said cutting mechanism bodily angularly to different positions about an axis substantially parallel to the direction of feed and to one side of the edge of the cutting mechanism, one of said positions being substantially vertical, and means whereby said cutting mechanism may be swept through arcs lying in planes which intersect within the material being cut, said planes substantially including said axis during the cutting operation.

19. A mining machine comprising cutting mechanism including a cutter bar and orbitally moving cutting means thereon operative to cut along the entire length of the bar, means whereby said cutting mechanism may be fed forward, means to guide it in its feeding movement, means to transport said cutting mechanism bodily to different positions about an axis substantially parallel to the direction of feed and disposed in a plane parallel to the plane of the bar, but outside the lines of projection of the edges of the bar on such plane, one of said positions being substantially vertical, means whereby said cutter bar may be swept when in each of said positions through an arc lying in a plane including a line substantially coincident with said axis during cutting operation, and means to turn said mechanism in planes parallel to said axis.

20. The combination with a mining machine adapted to slide upon its bottom upon a mine bottom during cutting and provided with a cutter bar, of means for supporting said machine during cutting in positions wherein said bar may cut kerfs in planes intersecting each other at an angle of ninety degrees along a line perpendicular to a working face.

21. The combination with a mining machine adapted to slide upon its own bottom on a mine bottom during cutting and having a cutter bar, of means for supporting said machine for cutting in a substantially vertical plane with the cutter bar thereof disposed at an acute angle to and above the horizontal.

22. In a mining apparatus, a support, cutting mechanism, a rotatable feed operating member, and means for supporting said cutting mechanism and said feed operating member on said support permitting change of plane of said cutting mechanism between substantially horizontal and vertical posi-

tions, said feed operating member being so related to said cutting mechanism that change of plane of the latter is accompanied by movement of the feed operating member 5 bringing the axis of rotation of the latter into a line parallel to a line making an angle with the original axis of rotation of said feed operating member.

23. In a mining apparatus, a support, cutting mechanism, a rotatable feed operating member, and means for supporting said cutting mechanism and said feed operating member on said support permitting change of plane of said cutting mechanism by movement about a horizontal longitudinally extending axis between substantially horizontal and vertical positions, said feed operating member being so related to said cutting mechanism that change of plane of the latter is accompanied by movement of the feed operating member bringing the axis of rotation of the latter into a line parallel to a line making an angle with the original axis of rotation of said feed operating member.

24. In a mining apparatus, a support, pivoted cutting mechanism mounted thereon and adjustable relative thereto to swing in substantially horizontal and vertical planes, and means for feeding said cutting mechanism including a feed operating member rotatable on an axis which bears a constant relation to the plane of cut irrespective of changes in the latter.

25. In a mining apparatus, a support, pivoted cutting mechanism mounted thereon and adjustable relative thereto to swing in substantially horizontal and vertical planes, and means for feeding said cutting mechanism including a feed operating member rotatable on an axis which is constantly perpendicular to the plane of cut irrespective of changes in the latter.

26. A mining machine of the cutter chain type including a chain with bits thereon and a chain guiding cutter bar pivotally mounted on a substantially horizontal axis, said bits cutting a kerf of a size to receive said bar, means for swinging said bar in a vertical plane, and guiding means for said mining machine along and between the ends of which said machine is rectilinearly reciprocable during cutting.

27. A mining machine of the cutter chain

type including a chain with bits thereon 55 and a chain guiding cutter bar pivotally mounted on a substantially horizontal axis adjacent the front end of the machine, said bits cutting a kerf of a size to receive said bar, means for swinging said bar in a vertical plane, and guiding means for said mining machine along and between the ends of which said machine is rectilinearly reciprocable during cutting.

28. A mining machine of the cutter chain type including a chain with bits thereon and a chain guiding cutter bar pivotally mounted on a substantially horizontal axis, said bits cutting a kerf of a size to receive said bar, and said machine being of a type 60 adapted to slide over a mine bottom while supported upon a surface parallel to the plane of the chain orbit, means for swinging said bar in a vertical plane, and guiding means for said mining machine along 65 and between the ends of which said machine is rectilinearly reciprocable with said surface in a substantially vertical plane during cutting.

29. In a mining machine, cutting mechanism including a cutter bar swingable in a vertical plane and having a circulating cutter chain thereon, supporting means for said bar, means carried by said supporting means for effecting swing of the bar in a vertical 80 plane, guiding means for said support, means for feeding said cutting mechanism and support along said guiding means including a rotatable element traveling with 85 said cutting mechanism, and means for permitting rotation of said support about a vertical axis.

30. In a mining apparatus, a support, a plane cutter bar provided with a cutter chain circulating around its periphery, and 90 supporting means for said bar whereby the same is mounted on said support permitting said bar to be swung in a horizontal plane, in a substantially vertical plane and in an oblique plane lying in the angle between the 95 horizontal and vertical planes, the kerf cut during swing of the bar in the oblique plane intersecting the zone of intersection of the horizontal kerf and the substantially vertical kerf.

In testimony whereof, I have signed my name to this specification.

PRESTON UPHAM.
